JAMES W. WESTON, OF NEW YORK, N. Y.

Letters Patent No. 86,193, dated January 26, 1869.

IMPROVEMENT IN FLOATS FOR LIFE-PRESERVERS, &c.

The Schedule referred to in these Letters Patent and making part of the same.

To all whom it may concern:

Be it known that I, JAMES W. WESTON, of the city and State of New York, have invented, made, and applied to use, a certain new and useful Improvement in Floats for Life-Preserving and Nautical Purposes; and I do hereby declare the following to be a full, clear, and exact description of the said invention, reference being had to the annexed drawing, making part of this specification, wherein—

Figure 1 represents one of my improved floats as partially broken open, to show the interior construction, and

Figure 2 is a cross-section of said float.

Heretofore floats have been made of inflated bags, that are liable to be pierced and destroyed. Also, they have been made of sheet-metal, which is subject to corrosion, indentation, and fracture, and is also heavy in proportion to its strength. Floats have also been made of cork and light wood, enclosed in a casing of sail-cloth, or similar material. These, however, are heavy to handle, and do not, consequently, support as much weight as they would if hollow, and lighter for the same bulk.

The nature of my said invention consists of a float, for life-preserving and nautical purposes, formed of a hollow casing, made of two or more laminæ of wood, with the grain of the wood running in different directions in the contiguous laminæ. Thereby I obtain great strength from the laminæ supporting each other, and the one preventing the other splitting; and hence I am able to make such floats very much lighter, and more buoyant, than heretofore.

I cover said floats with water-proof material, such as gutta-percha, so as to prevent the glue, or other cement employed for holding the laminæ together, becoming soft, and losing its adhesion.

In the drawing—

a and *b* are laminæ of wood, with the grain of one running in a different direction to the other, and *c* represents a third lamina, that might be used, or the laminæ still further increased in number.

These laminæ of wood are caused to adhere together by glue, or suitable cement.

The shape of the said float may be cylindrical, or of any other desired form. I have shown the same as cylindrical, with the heads inserted at the ends of the tube made of the laminæ aforesaid.

The head, *d*, is formed circular, with a flange to set at the end of the cylinder, as represented.

e is an exterior enclosing, of suitable material, such as gutta-percha or sail-cloth, in the latter instance, paint or varnish being employed to protect the float from the action of the water.

In order that these floats may be in convenient positions for use as life-preservers, or for nautical purposes, I attach them to stools, chairs, settees, or suspend long ones, to form the bottoms or sides of beds or hammocks; and these floats may be placed under the thwarts, or along the gunwales, of vessels, or be employed for life-rafts, or for any other nautical or marine purposes to which they may be available.

What I claim, and desire to secure by Letters Patent, is—

A hollow float, formed of a wooden casing, made of laminæ of wood, in the manner specified, and covered with water-proof material, for the purposes and as set forth.

Dated, March 25, A. D. 1868.

J. W. WESTON.
